UNITED STATES PATENT OFFICE.

ALBION D. T. LIBBY, OF ELYRIA, OHIO, ASSIGNOR, BY MESNE ASSIGNMENTS, TO THE GARFORD MANUFACTURING COMPANY, OF ELYRIA, OHIO, A CORPORATION OF OHIO.

COMPOSITE ELECTRIC SYSTEM.

1,137,152.

Specification of Letters Patent. Patented Apr. 27, 1915.

Application filed January 28, 1910. Serial No. 540,573.

To all whom it may concern:

Be it known that I, ALBION D. T. LIBBY, a citizen of the United States, residing at Elyria, in the county of Lorain and State 5 of Ohio, have invented certain new and useful Improvements in Composite Electric Systems; and I do hereby declare the following to be a full, clear, and exact description of the invention, such as will enable 10 others skilled in the art to which it appertains to make and use the same.

My invention relates to composite systems consisting in combined telephone and police systems, and more particularly to 15 those systems in which the means for calling the patrolmen are provided at the police boxes along the line of the patrolman's beat. Such systems are described in certain pending applications made by me, and I con- 20 template improvements upon these systems. I refer to application 515,044, Aug. 28, 1909; 540,571 and 540,572 Jan. 25, 1910.

I intend to utilize two conductors for purposes of telephoning, signaling the main 25 station, and for controlling the operation of the special signals at the substations or the patrolmen's boxes.

The telephone instruments consist of those 30 instruments usually provided at the substations for talking purposes. The police signal sending device consists in means for sending in signals to be delivered at the main station. These signals may also be recorded there. The signal at the patrol- 35 man's station consists of some attractive signal arrangement designated to draw the attention of the patrolman even though he be some distance from the box. This signal is controlled over the two conductors of the 40 telephone line, and may be operated over them as well.

The invention consists of the combination 45 of circuits and apparatus substantially as described in the detailed description and illustrated in the drawings, with such variations as the claims will admit when interpreted in view of the prior art and the description.

Referring now to the drawings, Figure 1 50 is one form of the circuit arrangement of my invention. Fig. 2 is a second form. Fig. 3 is a third form.

Referring first to Fig. 1, at A I show the 55 apparatus assembled at the police or main station. This apparatus is under the care

of an attendant. At C and D I show the apparatus which is assembled at the substations, or the police boxes. The substation apparatus consists of a telephone receiver S, the transmitter T, hook switch H and a 60 non-inductive resistance I connected in bridge of the two main conductors 1 and 2. In a second bridge of this line I show a condenser J and relay R⁴. The condenser J is adapted to be shunted by a short circuit 3. 65 This short circuit is controlled by the armature 4 of the relay R⁴. When direct current is thrown upon the system the current charging the condenser is sufficient to energize the relay R⁴ to close this shunt about 70 the condenser. Current thereupon flows through the relay and shunt to hold up the second armature 6. This armature is in a shunt of the relay R⁴ and condenser J and contains the lamp L. The lamp L is placed 75 within the patrolman's box and serves when illuminated to attract the attention of the patrolman. Connected in series in the circuit I show a police signal sending device E which opens and closes a switch in the 80 normally closed circuit. This produces an interruption of current in the system which causes the operation of the police signal receiving mechanism Q at the main station. At N I show a manually operated switch 85 which can be operated to interrupt the current of this circuit, sending impulses which are for the purpose of delivering a special signal at the main station. At the last station on the system I show a high inductive 90 resistance W connected in the circuit for a purpose to be described. At the main station the line relay is shown at R, and, connected in series therewith, a relay R⁵ which controls the operation of the police signal 95 receiving device. R^c is the relay of this device. The line signal controlled by the relay R is shown at L¹. At K I show the attendant's listening key. B² is a source of current which is used to operate the relays 100 R⁴ and the lamps L. The connection of this source to the line is controlled by a relay R³. A switch K, is used to initially operate this relay which immediately locks itself down. In the circuit of the source B² 105 I show a relay R² which controls a switch in the locking circuit of the relay R³.

The amount of current flowing through the circuit including the relay R⁴ or the lamp L is not great enough to energize this 110

relay. Upon removing the receiver from the hook, the low resistance of the telephone instrument circuit permits the flow of sufficient current to energize the relay R^2 , so that the circuit of R^3 is broken and the source of current B^2 is automatically disconnected from the line. At K^2 I show a switch for manually effecting the interruption of the locking circuit of R^3 . The flow of current through the normally closed circuit including the battery B, relays R^5 and R, the conductors 1 and 2, the police signal sending devices, and the resistance coil W, is sufficient to energize the relay R^5 , but insufficient to energize relay R. When a substation bridge is closed, the resistance W being shunted thereby, the current flow is sufficient to operate both R and R^5 . When the line circuit is interrupted at the armature contacts of R^3 , the relay R^5 would be de-energized and its armature released to operate the police signal receiving apparatus Q. To prevent this I provide a relay R^7 which is energized by the closure of key K^1 closing a circuit through relay R^5 independent of the line conductors.

The particular nature and the functions of the apparatus will be best understood from the description of the operation.

30 The operation is as follows: Should a patrolman desire to talk to the attendant at the main station, he removes his receiver from the hook, closing the switch H-7. A circuit is then completed from 7-1-8-9-35 10-11-winding 12 of R-winding 13 of R^5 -battery B-winding 14 of R^5 -winding 15 of R-16-17-18-19-2-S-T-H. The flow of current therethrough energizes the relay R which pulls up armature 20 closing a switch 20-21 and completing a circuit through the line lamp L^1 -from ground G-conductor 22-lamp L^1 -21-20-23-B-ground at G^1 . The attendant having observed this signal, throws over the listening key closing the switches 24-25, 26-27 and bridging on his telephone set. The talking circuit will be readily apparent and will not be described. Assuming that the receivers are on the hooks at the various police boxes 50 and that a patrolman desires to send in a signal to be received by the device Q and to be recorded thereby, he operates the motor-driven circuit interrupter E which opens and closes the following closed circuit: from 55 E-through conductor 2-to and through the relays R and R^5 -battery-back through conductor 1-resistance W-and the interrupter E. This circuit is, with the exception of the resistance W, the same as that 60 already traced. The current through this circuit will operate the relay R^5 which opens and closes the circuit of the relay R^6 which in turn controls the mechanism Q. These impulses, however, will be ineffective to operate the relay R. Should there be reason to

call the patrolman along the beat, the attendant at the central office will throw the key K^1 , closing a circuit through ground G—switch 28-29-conductor 30-relay R^3 -battery B³-ground G^2 . The relay R^3 will be energized, attracting its armatures 8, 19 and 31. The line circuit is broken at 18-19 and 8-9, and the current source B² closed upon the line at 8-32 and 19-33. At first the impulse of current flows from battery B²-33-19-to relays R^4 on one side, through relay R^2 -32-8-1-on the other side to charge the condenser J. This flow is sufficient to energize the relays R^4 which pull up their armatures 4 closing the switch 4-5 and the shunt 3 about the condenser J. Current then flows over this circuit through the said shunt and the relays R which lock up the armatures 6 closing the bridges of the lamps L which are now operated by current from this battery. As long as the resistance of any one of the devices: the relays R^4 , the lamps L, or the device W is in this circuit, the flow of current is not great enough to operate the relay R^2 . When a patrolman at one of the stations takes down the receiver placing the low resistance bridge of the telephone set across the lines, the current flow is immediately increased so that R^2 is energized to pull up 95 the armature 40, opening the switch 40-41 in the locking circuit of relay R^3 . This locking circuit will become effective immediately upon the energization of R^3 which may be traced as follows: ground— G^2 -battery B³-through the relay R^3 and the guard lamp L^2 in multiple—31-42-40-41—the key K^2 -to ground at G^4 . The interruption of this circuit causes the deenergization of relay R^3 which lets go its armature, disconnecting the source B² extinguishing the lamps and restoring the line circuit through to the attendant's listening key. During the interruption of the line circuit, the relay R^7 was energized first over a circuit from ground G-28-29-44- R^7 -battery B-to ground G^1 . Relay R^7 pulled up its armature 45, closing the switch 45-46 and locking itself through the conductor 47—switch 40-41-to ground at G^4 . Through this circuit the relay R^5 was maintained energized preventing the operation of the mechanism Q. The energization of the relay R^2 upon response at a substation, interrupted this circuit and again placed the relay R^6 under control of the interrupters in the line circuit. It will thus be seen that I have produced a combined telephone and police system in which the transmissions of various characters necessary to perform the desired communications, are conducted over two conductors.

Fig. 2 is a modified circuit, following in general the system of Fig. 1. In this, instead of using a source of continuous cur-

rent B^2 , I use an alternator X ; the current from this is adapted to operate the relay R^4 through the condenser J . This obviates the shunt 3. The police signal sending device Q and its associate relays R^5 and R^6 are connected to the conductors 1 and 2 on the line side of the contacts controlled by R^3 , so that it is unnecessary to provide any means for maintaining the circuit of the relay R^5 closed during the application of said current to line.

Fig. 3 is still another modification. In this system the lamps L are lighted over conductors independent of the telephone system and are controlled by the relays R^4 which may be energized by current from the alternator X which operates directly through the condensers J .

In Figs. 1 and 3 I show a switch 100—101 in the circuit of the line lamp L . This switch is controlled by the key K , and is opened when K is thrown to connect on the attendant's telephone set. The opening of the switch interrupts the circuit of the lamp L^1 and extinguishes the same. The voice currents are prevented from passing through the bridges of the relays R^4 by the reactance devices contained therein. The currents, however, may readily pass through the contacts of the members E and N . The lamp L^2 serves as a guard lamp indicating when the relay R^3 is energized or the fact that the source of lighting current is connected to the lamps L and that it has been disconnected or that response has been made at the substation.

While I have shown these particular forms of circuit and arrangement of apparatus, it will be obvious to those skilled in the art that numerous and extensive departures from the forms and the details thereof and the apparatus here shown may be made without departing from the spirit of this invention.

45 I claim:

1. In a composite system consisting of a combined police and telephone system, the combination of a main station, a plurality of substations, a pair of conductors connecting said stations, telephone instruments adapted to be connected in circuit with said conductors, police signaling and receiving apparatus connected in a series circuit with said conductors, lamp signals, and means for connecting said signals in circuit with said conductors, said means under control of the attendant at the main station.

2. In a composite system consisting of a combined telephone and police system, the combination of a main station, a plurality of substations, a pair of conductors connecting said stations, telephone instruments adapted to be connected to said conductors, signals at said stations, means for connecting said signals to said conductors, police

signal sending and recording apparatus operating over said conductors, a condenser in circuit with said means, said means operable by an impulse of current through the circuit of said condenser and when so operated adapted to shunt said condenser.

3. In a composite system, consisting of a combined police and telephone system, the combination of a main station, a plurality of substations, conductors connecting said stations, telephone instruments adapted to be connected to said conductors, police signal sending and receiving apparatus operating over said conductors, signals at said stations adapted to be connected to and to be operated over said conductors, relays controlling the circuit of said signals, a condenser in circuit with each relay, each relay adapted to be actuated by an impulse of current and when so actuated, shunting said condensers.

4. In a composite system, consisting of a combined police and telephone system, the combination of a main station, a plurality of substations, a pair of conductors connecting said stations, telephones adapted to be connected to said conductors, police signal sending and receiving apparatus operating over said conductors, signals at the substations adapted to be connected to said conductors, means operable over said conductors controlling said signals, the circuit of said means being impervious to a continuous current, and means to render said circuit permeable to such currents.

5. In a composite system consisting of a combined police and telephone system, the combination of a main station, a plurality of substations, conductors connecting said stations, said conductors being common to a telephone and a police signaling system, signals at said substations, relays operable over said conductors controlling said signals, the circuits being impervious to a continuous current, said relay adapted to be energized by an impulse of current through said conductor and when so energized operating to render its circuit permeable to continuous currents.

6. In a composite system, consisting of a combined police and telephone system, the combination of a main station, a plurality of substations, a pair of conductors connecting the same, telephone instruments adapted to be connected to said conductors, police signal sending and receiving apparatus operating over said conductors, signals at said stations adapted to be connected to said conductors, a source of current, means under control of the main station attendant governing the connection of said signals to said source, the circuit of the said means being impervious to continuous current, said means adapted when operated to render its circuit permeable to such currents.

7. In a composite system consisting of a

- combined police and telephone system, the combination of a main station, a plurality of substations, a pair of conductors connecting the same, telephone instruments adapting to be connected to said conductors, a signal at each station adapted to be connected to said conductors, a source of current, a relay at each station controlling the signal thereat, said relay under control of the main station attendant, a circuit for said relay impervious to continuous currents, said relay adapted when energized to change said circuit so that continuous currents may traverse the same.
8. In a composite system consisting of a combined police and telephone system, the combination of a main station, a plurality of substations, a pair of conductors connecting said stations, telephone instruments adapted to be connected in circuit with said conductors, police signal sending devices connected in a closed series circuit with said conductors, lamp signals at said substations, circuits therefor, and means controlling the circuits of said lamps connected in circuit with said conductors, said means controllable from the main station.
9. In a composite system consisting of a combined telephone and police system, the combination of a main station, a plurality of substations, a pair of conductors connecting said stations, telephone instruments adapted to be connected in circuit with said conductors, police signal sending devices connected in a closed series circuit with said conductors, lamp signals at said substations, circuits therefor, and means controlling the circuits of said lamps connected in circuit with said conductors, said means controllable from the main station over said conductors.
10. In a composite system consisting of a combined telephone and police system, the combination of a main station, a plurality of substations, a pair of conductors connecting the same, telephone instruments at the substations, adapted to be connected in circuit therewith, signal receiving devices at the main station responsive to the use of the telephone instruments, police signal sending apparatus operative to send signaling current over said conductors, lamp signals at the substations, means controlling said signals, said means governed over said conductors, and means to prevent interference among said devices, apparatus and lamp controlling means.
11. In a composite system consisting of a combined police and telephone system, the combination of a main station, a plurality of substations, a pair of conductors connecting the same, telephone instruments adapted to be connected in circuit with said conductors, police signal sending apparatus connected in a closed series circuit with said conductors, receiving means for the signals thereof at the main station, means for severing the connection between the said police signal sending and receiving apparatus, and means for closing a second circuit through the receiving device during the severance of said connection.
12. In a composite system consisting of a combined police and telephone system, the combination of a main station, a plurality of substations, a pair of conductors connecting said stations, telephone instruments at said stations adapted to be operated for conversational communication over said conductors, police signal sending apparatus, said conductors constituting a circuit therefor, lamp signals at said stations, said lamps controlled and operated over said conductors.
13. In a composite system consisting of a combined police and telephone system, the combination of a main station, a plurality of substations, a pair of conductors connecting said stations, telephone instruments at said stations adapted to be operated for conversational communication over said conductors, police signal sending apparatus, said conductors constituting a circuit therefor, lamp signals at said stations, said lamps adapted to be operated over said conductors, a source of current, and means under control of the main station attendant for connecting said lamps in circuit with said source.
